UNITED STATES PATENT OFFICE.

FREDERIC C. HOOD, OF BOSTON, MASSACHUSETTS.

RUBBER OVERTSHOE.

No. 867,882.

Specification of Letters Patent.

Patented Oct. 8, 1907.

Application filed April 10, 1907. Serial No. 367,432.

To all whom it may concern:

Be it known that I, FREDERIC C. HOOD, a citizen of the United States, residing at Boston, Massachusetts, have invented certain new and useful Improvements 5 in Rubber Overshoes, of which the following is a specification.

My invention relates to improvements in rubber overshoes which, while applicable in many respects to all kinds, is particularly useful in connection with over- 10 shoes of the class or type known as low cut or sole rubbers.

One object of the invention is to provide an overshoe having an upper with a reinforced or strengthened edge which will maintain its fit upon the boot or shoe until 15 the sole is worn out, which will be free from all liability of breaking or cracking, and which will effectually prevent the entrance of mud or water and the like between the shoe and rubber.

Another object is to provide a construction which, 20 when embodied in a low cut or sole rubber, will grip the sole so firmly as to remove all liability of accidental removal, and which will likewise prevent the entrance of foreign matter between the shoe and rubber.

With these and possibly other objects in view, the 25 invention comprises the construction hereinafter described, and particularly set forth in the appended claims.

The invention is illustrated in the accompanying drawings, in which:-

30 Figure 1 is a side elevation of an overshoe, partly in section. Fig. 1^a is an enlarged sectional detail of the toe portion. Fig. 2 is an enlarged transverse view on line 2-2 of Fig. 1. Fig. 3 is an enlarged detail view. Fig. 3^a is a section on line 3-3 of Fig. 3. Fig. 4 is a similar view of a modification. Fig. 4^a is a section on line 4-4 of Fig. 4. Fig. 5 is a similar view of another modification. Fig. 5^a is a section on line 5-5 of Fig. 5.

35 In this drawing I have shown for convenience only a low cut or sole rubber, which, except as hereinafter specified, may be of ordinary or any desired construction. In this drawing the numeral 5 designates the upper and 6 the sole.

40 I prefer to make the upper of a frictioned and coated fabric lining 11, an inner layer of frictioned fabric 8 cut on the bias, a reinforcing strip of frictioned fabric of suitable width between 8 and 11, as shown at 9, and an outer layer of compounded gum 7, all of which is 45 shown in detail in Fig. 3. An upper constructed in this manner is strong and durable and not liable to crack, break or become permanently stretched no matter how long the overshoe is worn, and it will maintain its snug fit against the surface of the leather boot or shoe. Where this construction is embodied in a low cut or sole rubber, it is desirable however to provide additional 50 means for retaining the rubber upon the foot of the

wearer. A very desirable manner of doing this is by providing a rubber strip 12 having an inwardly projecting integral bead or rib 13, the rubber strip having its inner face secured to the lining and extending around the inner side of the overshoe at such a distance from 60 the insole as to adapt it to fit over the edge of the sole of the leather boot, or shoe and into the groove between the sole and upper of the leather boot or shoe. In such construction the reinforced fabric of the upper, while affording sufficient elasticity to permit the overshoe to 65 be readily applied and removed, prevents any permanent stretching, thus insuring a snug fit during the entire lifetime of the overshoe, while the rubber bead carried by the lining and engaging the groove of the sole of the leather boot or shoe effectually prevents any accidental removal of the overshoe.

Instead of inserting an additional reinforcement strip of frictioned fabric, I may accomplish substantially the same result by folding or doubling over the upper edge of one of the fabric layers as shown at 14 in Fig. 4. 75

I may wish to make the upper part of the shoe very low and, therefore, raise the rubber strip, 12, to the top of the upper as shown in Fig. 5, the bead being 15.

I also may wish to make the inside bead 12 out of a 80 rolled or folded frictioned cloth.

I do not limit myself to these different constructions. I may wish to combine any of these or I may wish to put the bead nearer the insole in one spot than in another.

Having thus described my invention, what I claim is: 85

1. A rubber overshoe having in connection with the lining thereof a reinforcing strip of frictioned fabric located in proximity to the upper edge of the upper, substantially as described.

2. A rubber overshoe having its upper provided with 90 inner and outer layers of frictioned fabric and a reinforcing strip of frictioned fabric located between said layers and near the upper edge, substantially as described.

3. A rubber overshoe having incorporated in the upper thereof a layer of frictioned fabric, said frictioned fabric 95 having an upper edge portion folded upon itself forming a reinforcing strip, substantially as described.

4. A rubber overshoe having incorporated in the upper thereof, inner and outer layers of frictioned fabric, one of said layers being formed of a bias cut fabric, and a 100 reinforcing strip located between said layers, substantially as described.

5. A rubber overshoe having incorporated in the upper thereof inner and outer layers of frictioned fabric, said outer layer being formed of bias cut fabric and having its 105 upper edge folded over and lying between said inner and outer layers and forming a reinforcing strip.

6. A low cut rubber overshoe having a fabric lining and a beaded rubber strip secured to the inside face of 110 said fabric lining, substantially as described.

In testimony whereof, I affix my signature in presence of two witnesses.

FREDERIC C. HOOD.
